Inventor,
Hermann Doerr

United States Patent Office.

HEINRICH DOERR, OF MILWAUKEE, WISCONSIN.

Letters Patent No. 101,237, dated March 29, 1870.

IMPROVEMENT IN TRUNKS.

The Schedule referred to in these Letters Patent and making part of the same.

To all whom it may concern:

Be it known that I, HEINRICH DOERR, of the city and county of Milwaukee and State of Wisconsin, have invented a new and useful Improvement in Water-proof and Air-tight Trunks; and I do hereby declare that the following is a full, clear, and exact description thereof, which will enable those skilled in the art to make and use the same, reference being had to the accompanying drawing forming part of this specification, in which—

Figure 1 is an end view of my invention.

Figure 2, a back side view, showing the hinges.

Figure 3, a cross-sectional view in the line *xx*, fig. 2.

Figure 4, a sectional view of one of the hinges.

Similar letters of reference in each of the figures indicate corresponding parts.

The object of my invention is to produce a trunk that shall be water-proof and air-tight, and this I do by lining all the joints with rubber, and thus provide a life-preserved on the water, as well as to keep the contents safe from damage.

A is the body of the trunk.

B, the cover.

C, the bolts which fasten the top to the body of the trunk.

D, hinges.

E, spring in the hinge.

F, oblong opening in the hinge, which gives play to the hinge-pintle and lets the two parts of the trunk come together.

G, hasp or fastening to the trunk.

H, rubber joints or packing.

I, ring or stop on bolt C, to prevent its coming out and being lost.

K, clasps.

L, lock.

M, handles to the trunk.

Operation.

To make the trunk air-tight and of use as a life-preserved, and for the purpose of preventing the contents from destruction by water, shut down the cover B, and screw the bolts C into the clasps K. This will bring the cover down firmly onto the rubber packing, and make the trunk perfectly water and air-tight, the opening in the hinge allowing it to yield sufficiently for the purpose.

What I claim as my invention, and desire to secure by Letters Patent, is—

A water-proof trunk, when made with body A and cover B, bolts C, hinges D, spring E, oblong opening in the hinges D, which gives play to the hinge-pintle, rubber joints H, stop I on bolt C, to prevent loss, and clasps K, substantially as described.

HEINRICH DOERR.
